DESK-TYPE CIGARETTE LIGHTER

Samuel J. Koch, 821 Malcolm Road,
Burlingame, Calif. 94010

Filed Jan. 10, 1969, Ser. No. 15,309

Term of patent 14 years

Int. Cl. D27—05

U.S. Cl. D48—27

FIG. 1 is a front elevational view, showing my desk-type cigarette lighter.

FIG. 2 is a rear elevational view thereof.

FIG. 3 is a bottom plan view thereof.

FIG. 4 is an exploded side elevational view as viewed from the right in FIG. 1, the stopple member being removed in the operative position. The view from the opposite side is similar.

FIG. 5 is an elevational view taken along line 5—5 of FIG. 4, but showing the device assembled.

I claim:

The ornamental design for a desk-type cigarette lighter, as shown and described.
